CLAIM

The ornamental design for a bridge for auxiliary eyeglasses, as shown and described.

DESCRIPTION

FIG. 1 is a rear perspective view of a bridge for auxiliary eyeglasses showing my design;

FIG. 2 is a front elevational view thereof;

FIG. 3 is a rear elevational view thereof;

FIG. 4 is an enlarged left elevational view thereof;

FIG. 5 is an enlarged right elevational view thereof;

FIG. 6 is a top plan view thereof;

FIG. 7 is a bottom plan view thereof; and,

FIG. 8 is a front perspective view of the bridge for auxiliary eyeglasses in accordance with my design, shown in its environment thereof.

The broken lines shown in the FIGS. 1–8 are included for the purpose of illustrating environmental subject matter and form no part of the claimed design.
